UNITED STATES PATENT OFFICE.

MARTIN NYSTROM, OF CHICAGO, ILLINOIS, ASSIGNOR TO THE BRUNSWICK-BALKE-COLLENDER COMPANY, OF CHICAGO, ILLINOIS, A CORPORATION OF DELAWARE.

SUPPORTING STRUCTURE FOR THE OPERATIVE PARTS OF TALKING-MACHINES..

1,361,175.

Specification of Letters Patent.

Patented Dec. 7, 1920.

Original application filed May 20, 1918, Serial No. 235,472. Divided and this application filed August 16, 1919. Serial No. 317,884.

To all whom it may concern:

Be it known that I, MARTIN NYSTROM, a citizen of the United States, residing at Chicago, in the county of Cook and State of Illinois, have invented certain new and useful Improvements in Supporting Structures for the Operative Parts of Talking-Machines, of which the following is a specification.

10 This application is a division of my application Serial No. 235,472, filed May 20, 1918.

The object of this invention is to provide a supporting structure to receive the motor, 15 the tone arm and other movable parts of the operative mechanism of a talking machine so that the whole may be assembled and embodied as a unit in the talking machine cabinet.

20 A further object of the invention is to provide a strong and substantial supporting structure for the purpose indicated in which the movable parts are adapted to be readily mounted and maintained in their proper relation with each other.

25 And a further object of the invention is to facilitate the assembly of the motor, tone arm and other movable parts associated with the motor of a talking machine by providing a supporting structure of novel form and configuration and with the parts thereof so disposed and arranged that the said movable parts may be easily and conveniently arranged therein in proper position for operation and at the same time in a position which permits of inspection whenever desired for adjustment, oiling or other purposes.

30 In the accompanying drawings—

40 Figure 1 is a perspective view of the frame;

Fig. 2 is a top plan view of the top plate showing the frame and spring barrels in broken lines associated therewith;

45 Fig. 3 is a front elevation, partly in section, of the frame and top plate with the spring barrels indicated in broken lines;

50 Fig. 4 is a central sectional view showing the record table and tone arm in broken lines.

Referring to the drawings, the frame comprises two end members 5 and 6, the member

5 having the two end feet 5' and the member 6 having the centrally disposed foot 6' which constitute a three-point support 55 adapted to rest upon a plane surface during the assembling of the parts. The member 5 has outwardly projecting lugs 7 and 8 provided with aligned openings to receive the spindle 9 and with oppositely disposed inwardly projecting lugs 10 and 11 to receive the shaft which is driven by the usual springs contained in spring barrels 12 and communicates motion to the spindle. Other lugs 13 project outwardly from the member 65 5 to support the governor shaft. The two members 5 and 6 are provided with aligned bearings 14 for the shaft which supports the spring barrels and the gears 15 which are driven thereby. Ears 16 projecting outwardly from the member 5 are provided with openings to receive the brake rod and ears 17 projecting inwardly from the member 6 are provided with openings to receive the winding shaft. The movable parts of 70 75 what may be referred to generally as the motor mechanism and herein mentioned are disclosed in the aforesaid application and more particularly in a preferred form in my companion application Serial No. 80 317,885 filed concurrently herewith.

The two end members of the frame are provided at the top with flat bed sections 18 whose upper surfaces lie in a horizontal plane to receive the top member 19 of the 85 frame, and the several members are rigidly secured together by screws 20. This top member has an opening 21 to accommodate the spindle and to permit access to the driving shaft, and it also has openings 22 which 90 permit access to the spring barrels, but which are principally provided to lighten the weight. At one corner of the top member there is a projection 23 provided with an opening to receive the speed regulating 95 device, and bosses 24 having threaded openings therein are disposed about the top member.

The top plate 25 is fastened to the top members of the frame by screws 26 which 100 engage the threaded openings in the bosses 24. This top plate covers the frame and the parts supported thereby and it is of a proper size and shape to fit a corresponding

opening in the top board of a talking machine cabinet in which it is suitably supported. The top plate has an integral rear extension 27 provided with an opening to support the tone arm 28, also integral projections 29 at one side to form a protection for the operating handles of a brake mechanism and a corner extension 30 to receive the speed control device which is disclosed in 10 a preferred form in my companion application Serial No. 317,882 filed concurrently herewith.

My invention provides a simple but effective means for conveniently and accurately 15 assembling the mechanical operative parts with the cabinet to produce a modern talking machine. These mechanical parts are made in a machine shop and the cabinet is usually made of wood and produced in a 20 woodworking plant. It has been customary to assemble the mechanical parts and the cabinet in an assembly room and to make the top plate of wood. If the mechanical parts are produced at a distance from the 25 cabinet and the parts are shipped to a place of assembly, considerable difficulty is encountered in obtaining a proper fit and co-operation of the parts, and the work of assembly has involved more or less fitting and 30 adjusting and thereby increased the cost of production. My invention provides a means whereby all the mechanical operative parts may be assembled as a unit in a machine shop or in an assembly place where they can 35 be properly adjusted and given a final test, and this unit may be transported to another place and embodied in a cabinet prepared for it without further test and with absolute 40 assurance that the mechanism will work in the intended manner. This is of great importance in the commercial art because the cabinets and the operative parts are often made in different places and have to be 45 shipped to a place of assembly for completing the machines. The construction of the frame permits the operative parts to be assembled and tested in a convenient manner on a bench or table under the same conditions, to all intents and purposes, that 50 would exist if these parts were assembled directly in the cabinet. The invention not only materially reduces the cost of assembly in the production of a talking machine but it enables the operative parts to be easily 55 disconnected from the cabinet as a unit for inspection or replacement or for oiling or any other purpose.

I am aware that changes in the form and proportion of parts and in the details of 60 construction may be made without departing from the spirit or sacrificing any of the advantages of the invention, and I therefore reserve the right to make all such changes as fairly fall within the scope of 65 the following claims.

I prefer to make the frame of metal in three parts, as herein described and I also prefer to make the top plate, which corresponds to the motor board in an ordinary machine, of pressed metal in a single part, 70 but the material and number of parts may be changed as found desirable. •

I claim:

1. A supporting structure for the mechanical operative parts of a talking machine 75 comprising a frame having two end members and a top member fastened together, one of said end members having feet at its ends and the other end member having a single centrally disposed foot to support said frame in a horizontal position.

2. A supporting structure for the mechanical operative parts of a talking machine comprising a frame having two end members and a top member fastened together, 85 said top member having a lateral extension to support the speed adjusting device of the machine.

3. A supporting structure for the mechanical operative parts of a talking machine 90 comprising a frame having two end members and a top member fastened together, one of said end members having integral alined lugs projecting outwardly therefrom to support the driving shaft of the machine. 95

4. A supporting structure for the mechanical operative parts of a talking machine comprising a frame having two end members and a top member fastened together, one of said end members having integral alined lugs to support the spindle of 100 the machine.

5. A supporting structure for the mechanical operative parts of a talking machine comprising a frame having two end members and a top member fastened together, one of said end members having integral alined lugs to support the governor 105 shaft of the machine.

6. A supporting structure for the mechanical operative parts of a talking machine comprising a frame having two end members and a top member fastened together, one of said end members having integral alined lugs to support the spindle 115 and the driving shaft of the machine and said top member having an opening therein to accommodate the spindle and to permit access to the driving shaft.

7. A supporting structure for the mechanical operative parts of a talking machine comprising a frame having two end members provided with bed sections at the top thereof, a top member fastened to said bed sections, and feet on said end members 125 to support the frame in a horizontal position.

8. A supporting structure for the mechanical operative parts of a talking machine comprising a frame and a top plate 130

fastened to said frame, said top plate having an integral rear extension to support the tone arm of the machine.

9. A supporting structure for the mechanical operative parts of a talking machine comprising a frame and a top plate fastened to the frame, said top plate having integral therewith a rearward extension to

support the tone arm, a corner extension to receive the speed controlling device, and side 10 extensions to form guards for the brake levers.

MARTIN NYSTROM.
